UNITED STATES PATENT OFFICE

CHARLES T. HOFFMAN, OF WASHINGTON, DISTRICT OF COLUMBIA, ASSIGNOR OF ONE-HALF TO EMORY L. GROFF, OF WASHINGTON, DISTRICT OF COLUMBIA

REFRIGERATOR

Application filed May 15, 1930. Serial No. 452,687.

This invention relates to refrigerators of the household type and more particularly to improvements therein, carrying forward the essential features set forth in my copending application Serial 400,888 filed October 5, 1929.

One of the objects of the invention is to provide means for illuminating the interior of the box in a practical and simple manner. According to my application aforesaid it is proposed to utilize a visual indicator in the form of a lamp for indicating the defrosting cycle or period. In the present construction it is proposed to utilize this lamp not only for the purpose just stated but also to illuminate the interior of the box upon the opening of the refrigerator door. In that connection it is proposed so to locate the lamp that it is entirely concealed within a wall of the cabinet but the lamp box is provided with windows or openings which not only render the illuminated lamp visible from the front of the box but also permits the lamp to amply illuminate the interior or food compartment of the box. This novel arrangement locates the lamp in such a way that it is entirely outside of the food compartment and at the same time all the wiring connections leading thereto are embedded 25 in a wall of the box thus not only preventing breakage of the lamp by the placing of articles in the box but also rendering the electrical installation entirely safe.

Another object of the invention is to provide a novel switch mechanism which is actuated by electro-magnets supplied with current from a bell-ringer transformer, or the like, which may be connected with a standard 110 volt source of supply while at the same 35 time permitting the reduced voltage used in the magnets to be utilized in the push-button circuit through which the owner of the box initiates the defrosting period. A feature of the switch mechanism shown and described herein is that the swinging movement of one of the oscillating switch arms is temporarily arrested in a part of its movement thereby to prevent the locking of the motor "off" in event the push-button circuit is closed by mistake or design while the

circuit of the thermostat on the coils or coil baffles is closed. In other words, the present switch has a delayed movement which effectually prevents the condition above referred to.

With the above and other objects in view which will more readily appear as the nature of the invention is better understood, the same consists in the novel construction hereinafter more fully described, illustrated, and claimed.

A preferred and practical embodiment of the invention is shown in the accompanying drawings, in which:

Fig. 1 is a front elevation of a portion of an icebox illustrating the lamp feature of the invention.

Fig. 2 is a vertical cross-sectional view taken on the line 2-2 of Fig. 1.

Fig. 3 is a detail cross-sectional view taken on the line 3-3 of Fig. 1.

Fig. 4 is a detail sectional view of the door switch.

Fig. 5 is a diagrammatic view illustrating the combination of the push-button switch, defrosting lamp, door control switch, thermostat switch, and automatic switch device operating with both high and low voltage currents.

Fig. 6 is a plan view of the complete automatic switch.

Fig. 6a is a detail top plan view of the mercury container carried by the movable switch arm.

Fig. 6b is a detail view illustrating more fully the delayed action feature of the switch.

Fig. 7 is a detail vertical sectional view taken on the line 7-7 of Fig. 6.

Fig. 7a is a detail view illustrating the application of a non-tilting mercury container to the movable switch arm.

Similar reference characters designate corresponding parts throughout the several views.

Referring to Fig. 1 the cabinet or icebox is designated generally as A, the same being of the usual type now generally on the market and having the door B for closing and permitting access to the compartment which houses the evaporator and the food.

Above the door B there is preferably arranged a suitable face plate C having therewith a push-button D and a lens E. The lens E covers the front end of an opening or window F formed in the frame member F' of the box which communicates with a lamp box G so that when the lamp H is illuminated the light therefrom will be visible through the lens. The said lamp box G is concealed within a wall of the box or cabinet A and is provided with an opening or window G' which may be covered in any suitable manner by a glass or other transparent element I located within the food compartment of the box and at the inside of the door B. Thus, the lamp H is intended to be illuminated during the defrosting period as will hereinafter appear. Also when the door B is opened, the closing of the door switch B' will cause the lamp to be illuminated and the interior of the cabinet will be flooded with light, while at the same time the lens E will be illuminated.

The door switch B' may be of any conventional type which breaks the circuit when the door B is closed and on the other hand closes the circuit when the door is open. The circuit connections for the lamp H are such that whenever the user of the box opens the door the interior of the box will be flooded with light, and even though the door is closed, when the defrosting period occurs the lamp will be illuminated by the closing of the circuit through the automatic switch designated generally as S (Fig. 5). Therefore, while the box is defrosting the user of the box will know the condition of the box through the illumination of the lens E even though the door is closed, and if the box is opened during the defrosting period the interior of the cabinet will still be flooded with light, the opening and closing of the door having no effect thereon.

Before proceeding to a description of the circuits involved in the present combination features, it may be pointed out that the push-button device D illustrated in detail in Fig. 3 may also be of any conventional and well-known type on the market and therefore a detailed description thereof is unnecessary.

Referring now to Fig. 5 of the drawings, the various parts are shown in the defrosting position, that is, the position when the circuit to the motor of the refrigerating apparatus is broken and the lamp H is illuminated, thus rendering the door switch B' inoperative since the circuit is shunted therewith while the thermostat switch T on the evaporator is open. It may be pointed out that this latter switch remains open until the food compartment of the box warms up to the predetermined degree thereby to automatically close the circuit to the switch device S and throw the same to its other position

to again close the circuit to the motor of the refrigerating apparatus.

The push-button D is connected by the wire d to the low voltage binding post R of the bell-ringer transformer U. The bell-ringer transformer U is connected to the 110 volt current supply by the wires u and u'. When the switch arm 2 is in the dotted line position shown in Fig. 5 the circuit from the push-button D will be closed from the binding terminal R of the transformer through the transformer itself to the binding terminal R' thereof and thence through the wire m to the electro-magnet M which is connected by the wire m' with the electro-magnet M', and thence through the wire n to the conductor 3 carried by the end of the switch arm 2 which is engaged with the contact 1. Thus the circuit is completed from the push-button through the electro-magnets M—M' which will cause the energization of the armature O and cause the movement of the link 4 connected therewith, which in turn will cause the movement of the arm 5 to which it is pivotally connected as indicated at 5a thereby to cause the movement of the head 6 carried by the arm to engage with the sliding dog 7 and move the switch arm 2 to the full line position shown in Fig. 5. The switch S is then in the defrosting position as indicated by the legend on the drawings.

When the switch S is in the so-called defrosting position the lamp H will be illuminated, and the circuit which causes the illumination of the lamp will now be traced. Starting with the current supplied by the 110 volt source, the same passes over the line u' to the conductor 8 which is connected with the inside terminals 9 of a tilting mercury tube 10 which is carried by the actuating arm 11. The actuating arm 11 and the switch arm 2 are pivoted on the common axis 12 and are held in the position to which they are thrown by the action of the member 6 and dogs 7 and 7a by the tensioning spring 13.

When the mercury tube 10 is tilted to the position shown in Fig. 5 the mercury 14 in the tube closes the circuit between one of the inside terminals 9 and the outside terminal 9a. This terminal 9a is connected by the wire 15 with one of the terminals of the lamp H and after the current passes through the lamp it returns to the 110 volt line u over the wire 16. As long as the defrosting cycle continues the circuit will be closed through the lamp H in the manner just described, and it will, of course, be understood that the defrosting cycle continues until the circuit over the low voltage line is again closed by the thermostat switch T mounted on the evaporator.

Assuming that the frost or ice has completely left the coils and baffle plates of the evaporator and the box has warmed up to the predetermined temperature, the thermostat switch T automatically closes the cir-

cuit through the electro-magnets $M-M'$ to again cause the actuation of the armature O and cause the head 6 to engage with the dog 7 and throw the switch arm 2 from the full line position shown in Fig. 5 to the dotted line position which closes the circuit to the motor of the refrigerating apparatus.

The circuit will now be traced from the thermostat switch T through the switch S .

- 10 Immediately upon the engagement of the contacts t and t' of the thermostat switch T the low voltage circuit will be closed from the contact t over the line 17 which is connected with the contact $1a$ of the switch S . From thence the current will pass through the conductor 3 over the line n to the electro-magnet M' which is included in circuit with the electro-magnet M as previously described, and the latter in turn is connected with the bell-ringer transformer U at the terminal R' . The other terminal R of the bell-ringer transformer is connected with the line d' which has connected thereto at any suitable point the wire 18 leading to the contact t' of the thermostat T . When the circuit is thus completed the armature O actuates the shaft 5 and causes the head 6 to engage the dog 7 , thus moving the arm 2 to the dotted line position and returning switch contacts 1 and 3 into engagement and also tilting the mercury tube T to the position opposite to that shown in Fig. 5, thereby to throw the mercury 14 to the other end of the tube to thus close the circuit between the right-hand inside contact 9 and contact $9b$. The contact $9b$ is connected by the wire 19 to the motor of the refrigerating apparatus, and the latter is connected by the wire 20 with the line u of the 110 volt current supply. In that way the circuit is closed to the motor of the refrigerating apparatus and the refrigerator assumes the refrigerating cycle, the usual operative switch controlling the circulation of the refrigerant having meantime been or become closed by virtue of the box having warmed up during the defrosting period.

The door controlled switch B' has one of its terminals b' connected by the wire 21 with the 110 volt line u' , and its other terminal b' is connected by the wire 22 with one of the terminals of the lamp H . The other terminal of the lamp is connected with the wire 16 which is the return wire line for the lamp circuit which is common to both the defrosting circuit and the door controlled circuit for the lamp. It is pointed out that the wire 15 of the defrosting circuit is connected to the wire 22 in such a way that when the circuit is closed through the switch S on the defrosting cycle the door controlled switch contacts are shunted. Therefore, when the door is closed the lamp will remain illuminated to indicate the defrosting cycle through the lens E but if the door B should be opened

the closing of the switch B' will have no effect on the lamp. This is an important and essential feature of the arrangement described which enables the use of a common source of light for indicating the defrosting cycle as well as illuminating the interior and contents of the box.

Having now set forth the general operation of the various units, the important and distinctive feature of the delayed action operation of the switch S will be described.

As soon as the contacts t and t' of the thermostat T are closed the switch arm 2 is thrown from the full line position shown in Fig. 5 to the dotted line position. The thermostat switch is necessarily more or less slow acting since it is controlled by box temperature warming up to close the contacts and the lowering temperature of the evaporator coils after the refrigerating cycle is again started to open the contacts. Thus, there are a few minutes after the motor has been switched on again, after the defrosting period has ceased and the light H extinguished, that the contacts t and t' are still in engagement.

Now if by accident or design the push-button D is pressed while the said contacts t and t' are in engagement, such closing of these contacts will have no damaging effect on the switch or the motor of the refrigerating apparatus. That is to say, under no circumstances can the motor of the refrigerating apparatus be locked in an inoperative position due to switch arm 2 again being thrown back to the full line or defrosting position shown in Fig. 5, which position it has just left due to the closing of the contacts t and t' .

Assuming for example that the switch arm 2 has been thrown to the dotted line position in Fig. 5, which as previously indicated immediately cuts the refrigerating motor in circuit and the contacts t and t' of the thermostat are still engaged, and the push-button D is pressed or held in, the electro-magnets M and M' will, of course, be energized by the closing of the push-button circuit. The spring controlled armature O being actuated by the magnets will cause the plunger $5-6$ to pull the dog $7a$ and throw the arm 11 over against the tension of the spring 13 which pulls arm 2 back partially toward the full line position where it remains temporarily until the plunger $5-6$ moves back to its full return stroke, permitting dog 7 to drop off the front edge of the plunger member 6 thereby permitting conductor 3 and contact $1a$ to engage. These contacts are still alive under this condition due to the contacts t and t' of the thermostat T being still in engagement. So long as the circuits are both closed through the push-button D and the thermostat T this action will be repeated with the other dog $7a$. In this way the armature O functions substantially as a motor

operating to alternately throw the arm 11, and consequently the arm 2, first toward the contact 1a and then toward the contact 1 until the push-button is released, whereupon 5 the switch lands in the "motor on" position. In other words, so long as the thermostat contacts t and t' remain closed the effect of the energization of the magnets M and M' will be to throw the switch arm 2 to the 10 "motor on" or dotted line position shown in Fig. 5, and naturally as soon as the circuit is broken through the push-button circuit the switch arm will remain in the "motor on" 15 position, that is with the contact 1 in engagement with the conductor 3, or will immediately be thrown to that position. This action of the switch is intended to make the operation of the switch S entirely fool proof under all conditions of use.

20 The mechanical features of the switch S, which insure the fool proof action just described, will now be referred to more in detail.

As previously indicated, the switch arm 2 and its companion switch arm 11, which carry 25 the mercury tube 10 are mounted on a common axis 12. The arm 2 is provided with suitable guides for receiving the shanks of the dogs 7 and 7a, and the said shanks of the dogs 30 are provided with the offset projections 7b for engaging with the switch arm 11 as the heads of the dogs are alternately engaged by head 6 of the plunger. The arms 2 and 11 are connected by the tension spring 13 in such 35 a way that when the conductor 3 of the switch arm 2 is held against either contact 1 or 1a, the upper end of the arm 11 is engaged with one of the stops 11a, which stops limit the movement of said arm 11. When 40 the armature O is moved against the tension of its spring o by the energization of the magnets M and M', thereby to move the plunger 5-6, the head 6 of the plunger will first engage, for example, the head of the dog 7 which lies in its path of movement as shown 45 in Fig. 5. The movement of the shaft 5 of the plunger will pull the dog 7 through its guide on arm 2 and cause the offset portion 7b of the dog 7 to engage the arm 11 and move it against the tension of the spring 13. When 50 the arm 11 has moved sufficiently to cause the spring 13 to pass the center of the axis 12, the energy of said spring will snap the switch arm 2 away from the contact 1a, thus 55 elevating the dog 7 and causing it to clear the end of the plunger head 6 with which it has been engaged. The head of the dog 7a will then be thrown on to the relatively long edge 6a of the plunger head where it will remain 60 temporarily and likewise temporarily hold the switch arm 2 away from its receiving contact 1, thereby permitting the plunger 5 to fully return to its normal position under the influence of the spring tensioned armature O. When the plunger 5-6 nearly reaches the 65 end of its movement due to the spring o pull-

ing on the armature O, the dog 7a will slip in front of the head of the plunger 6 and the switch is ready for the next actuation. Immediately upon the head 6 of the plunger pulling the dog 7 a sufficient distance to cause 70 the arm 11 to pass dead center, the switch arm 2 is moved away from the contact 1a, thus breaking the contact between 1a and conductor 3. However, due to the fact just stated, namely, that the dog 7a rides on the 75 edge 6a of the head of the plunger, the return of the conductor 3 toward its receiving contact is temporarily delayed, thereby permitting the plunger to get back to the original position from which pulled, its return 80 being effected by the spring o upon the opening of the contacts to the magnets.

The same action just described in connection with the head 6 of the plunger and the dog 7 will occur in relation to the head 6 of the 85 plunger and the dog 7a on the next movement of the armature O. Thus, it will be observed, that the elongated 6a of the plunger performs two important functions. First, it lets the plunger get back to its original position upon the opening of the circuit to the electro-magnets by permitting the spring o to force the plunger back to its original position; and, second, this delayed action holds 90 the conductor 3 away from its receiving contact temporarily until the plunger is in position to engage the proper dog necessary for 95 actuation of the switch in the opposite direction to that which it has just left.

While the switch mechanism S has been 100 described and shown in connection with low voltage on the contacts 1-1a and conductor 3, which are included in the push-button-thermostat switch circuits, nevertheless it will, of course, be understood that this switch 105 mechanism may be utilized when and where desirable to handle commercial voltages, and particularly so adapted because of the quick action of the arm 2. Therefore, it will be apparent that the magnets M and M' and the armature shown in the embodiment of the invention in Figs. 5 and 6 merely serve 110 as an actuator for the plunger 5-6, and the necessary changes in the actuator to adapt it to also handle commercial voltages are well 115 within the skill of anyone versed in the art.

In the embodiment of the switch device S shown in Fig. 6 precisely the same elements 120 previously described in connection with Fig. 5 are used. However, for the purpose of illustrating the adaptability of this switch to a commercial form all of the various switch parts are shown as being mounted on a base 125 which may also serve to conveniently carry the binding post blocks 26 and 27. The block 26 carries the terminals for the low voltage connections and block 27 carries the terminals for the high voltage connections, all of 130 which are marked in accordance with the diagram, Fig. 5. The entire mechanism car-

ried by the base 25 may be placed within a suitable metal box or case 28 having the knockout openings indicated at 29 in the conventional manner. While the cover is not shown for the box 28, it, of course, may be provided with such cover in accordance with standard practice.

A further novel and distinctive feature of the present invention is shown in Fig. 7a. In 10 this figure the arm 11 is shown carrying a glass disc-like container 30 for containing mercury or other conductive fluid and having associated therewith the terminals 31, 32, and 33. The container 30 may be mounted in any 15 suitable manner on the arm 11 as, for example, through the medium of the bracket 34, which is carried by the arm 11 in such a way that as the arm is shifted from one position to another the glass or other insulated 20 container will move but the mercury will maintain a relatively constant position. In other words, when the arm 11 moves the contacts 31 and 32 carried by the container will be shifted into and out of the mercury, while 25 the contact 33 remains immersed therein. In the illustration given, the contacts 31 and 33 would be used for closing the circuit to the lamp H, while the contacts 32 and 33 would be used to close the circuit to the motor of 30 the refrigerating apparatus. The advantage of the use of this type of shiftable contactor is that it requires less energy to move the switch arm, since the mercury is not shifted as in the tilttable type mercury tube, 35 nor is there any inertia to overcome as in the elongated tube type of conductor due to the mercury being held at one end of the tube until the tube itself is tilted in the opposite direction.

40 I claim:—

1. In a refrigerator cabinet, the combination with the food compartment having a wall, a lamp compartment formed in said wall and having windows respectively opening 45 at the outside of the cabinet and into the food compartment, a lamp in said lamp compartment, a switch for controlling the illumination of the lamp, and manually operated means for initiating the operation of said 50 switch.

2. In a refrigerator cabinet, the combination with the food compartment having a door, of a wall of the cabinet having windows, opening respectively at the outside of the 55 cabinet and into the food compartment, a lamp arranged in illuminating relation to said windows, an automatic door controlled switch, and an automatic defrosting switch, both of said switches being included in circuit with the lamp.

3. In a refrigerator cabinet having a food compartment, a door, an evaporator located in said compartment, and a motor for circulating refrigerant in the evaporator; the 65 combination of a lamp housed within a wall

of the food compartment, means in said wall of the food compartment for permitting the lamp to illuminate the food compartment, means for rendering the lamp visible from the outside of the cabinet, a circuit including the lamp and both manual and automatic means for controlling the circuit to the lamp and the motor, and door operated switch means also included in circuit with the lamp.

4. In a refrigerator cabinet having a food compartment, a door, an evaporator located in said compartment and a motor outside of said compartment for circulating refrigerant in the evaporator; a wall of the cabinet having windows opening to the outside of the cabinet and at the inside into the food compartment, a lamp arranged in illuminating relation to said windows, separate switch devices respectively adapted to be manually and automatically operated for controlling the circuit to the motor and the lamp and a door operated switch also included in circuit with the lamp and controlled by the manual opening and closing of the door.

5. Means for automatically defrosting refrigerating units of refrigerators equipped with electrically operated means for circulating a refrigerant in the unit and means for maintaining said unit within predetermined temperature limits, comprising the combination with the current supply line to said electrically operated means, of a switch device located in said current supply line anterior to the refrigerating apparatus, thermal responsive means for operating the switch to control the circuit, said switch comprising a pair of switch arms pivoted about a common axis, a spring connecting said arms, electro-magnetically operated means for operating one of said switch arms, and means for temporarily delaying the full action of the other arm.

6. Means for automatically defrosting refrigerating units of refrigerators equipped with electrically operated means for circulating a refrigerant in the unit and means for maintaining said units within predetermined temperature limits, comprising the combination with the current supply line to said electrically operated means, of a thermal responsive member associated with the refrigerating unit, a switch device in said current supply line anterior to the refrigerating apparatus including a pair of pivoted spring connected switch arms, electro-magnetically operated means, said thermal responsive element, switch, and electro-magnetic means being included in circuit, and means controlled by said electro-magnetic means for temporarily delaying the full operation of one of said switch arms until the electro-magnetically operated means returns to its normal position.

7. Evaporator defrosting means for electrically operated refrigerators comprising a

thermal responsive switch associated with the evaporator, a manually operated switch, and an automatically operated switch including electro-magnetically operated means, a pair of pivoted spring connected switch arms, means carried by one of said arms adapted to be engaged by said electro-magnetically operated means whereby one of said arms is permitted to make its full stroke while the other is prevented from making its full stroke until said electro-magnetically operated means returns to its normal position.

8. A refrigerator cabinet having a food compartment provided with a door, said cabinet also having an opening providing a window, a lamp arranged in illuminating relation to said food compartment and window, a door controlled switch, and a defrosting switch, both of said switches being included in circuit with the lamp.

In testimony whereof I affix my signature.
CHARLES T. HOFFMAN.
